UNITED STATES PATENT OFFICE

142,870

DESIGN FOR A COMBINATION CIGARETTE CASE AND COMPACT

Ludwig Katz, Providence, R. I.

Application March 12, 1945, Serial No. 118,413

Term of patent 7 years

(Cl. D86—10)

To all whom it may concern:

Be it known that I, Ludwig Katz, a citizen of Germany who has applied for citizenship in the United States, residing at Providence, in the county of Providence and State of Rhode Island, have invented a new, original, and ornamental Design for Combination Cigarette Case and Compact, of which the following is a specification, reference being had to the accompanying drawing, constituting a part thereof.

Fig. 1 is a perspective view of a combination cigarette case and compact with the covers in open position, showing my new design;

Fig. 2 is a top plan view thereof with the covers in closed position; and

Fig. 3 is a side view of Fig. 2.

I claim:

The ornamental design for a combination cigarette case and compact, substantially as shown.

LUDWIG KATZ.
